ROTARY MILL FEED

Levigne Moritz Zepp, Westminster, Md., assignor to Pittsburgh Plate Glass Company, Columbia Chemical Division, Zanesville, Ohio, a corporation of Pennsylvania.

Application July 28, 1931, Serial No. 553,506

3 Claims. (Cl. 83—9)

In the operation of rotary mills of the type which are axially fed and generally continuous in their operation, one of the difficulties heretofore encountered is the tendency of the bearings supporting the rotating container which is usually a cylinder to wear, permitting the container to settle and throw the axial feed pipe out of line, so that cramping and leakage result.

Another difficulty is incident to the regulation 10 of the feed in accordance with the quantity of material presented.

The invention relates in general to a feed for 15 rotating mills, first, to an adjustment of the feed pipe in connection with and in proportion to the wear on the supporting bearings and the consequent settlement of the cylinder, and secondly, to a method of regulating the flow of material 20 to the mill.

By means of the invention the difficulties referred to have been eliminated or minimized.

The invention embodies and provides means for measuring or indicating the settlement of the bearings of the cylinder itself and means for adjusting the alignment of the feed pipe in accordance 25 with the readings of the indicating means and hence in proportion to or in exact equality with the settlement of the cylinder or container whereby the alignment of the feed pipe with the bearings is maintained.

The invention further relates to the construction 30 of a feed pipe whereby the static pressure or head of the material within the pipe due to accumulation of material therein is caused to apply a corresponding pressure at the feed opening, regulating the flow of material to the mill proportionately to the supply of material presented to the mill to be ground.

To regulate the feed to the supply, the feed pipe extends upwardly to an elevation sufficient 40 to establish a pressure due to the height or head of material in the pipe which serves to force the material which is of a fluid or some fluid material into and through the mill at the desired rate. When it is the intent of the operator to increase 45 the flow, the material is fed more rapidly and maintained at a higher level within the pipe increasing the feeding pressure, and when the flow is to be retarded, the material being fed is maintained at a lower level, reducing the pressure. Thus the flow of material through the mill is 50 controlled by maintaining the accumulation of material at various levels within the feed pipe, determined by the rate at which the material is supplied, the pressure and hence the rate of

feed being proportionate to the head, and hence to the supply.

A clear conception can be had of the present invention by referring to the accompanying drawing wherein like characters of reference denote 60 corresponding parts in the several views.

In the drawing:

Figure 1 is a fragmentary vertical longitudinal section through a rotary comminuting mill embodying the improvements.

Figure 2 is an enlarged transverse vertical section taken on the line 2—2 in Figure 1.

Figure 3 is an enlarged fragmentary vertical section of the adjustable feed pipe supporting means.

Figure 4 is an enlarged horizontal plan view of the ratchet wheel removed.

Referring to the drawing, the machine shown and in connection with which the invention has been developed, the features of which machine are not in the main essential to the invention, consists of a rotary continuously operating comminuting mill of the type comprising an elongated drum 3 supported for rotation about a horizontal axis by means of hollow trunnions 1 and 1' turning in suitable bearings 4 and 5, and adapted to be driven by toothed gear 50. Connected to the outer portion of the trunnion 1 which rotates in bearing 4, is a flange 6 or any suitable means secured to the drum structure in the vicinity of trunnion 1 and concentric with the axis of the drum to operate in combination with the indicating element of the invention.

The feed of the material to the mill as illustrated in the drawing is by way of the axis, the stationary feed pipe 7 which delivers to the drum by way of hollow trunnion 1 being inserted in the trunnion 1 and connected to the same by a packing gland at 8. This stationary pipe 7 is connected to an upright feed pipe or stand pipe 9 by a suitable union 8' and elbow 11. A packed slip joint 10 is provided between two sections 9' and 9'' of the upright feed pipe 9 to allow for the vertical motion of the elbow 11. This elbow is shown as rigidly connected to the stationary feed pipe 7, whereby the movement of the elbow 11 relatively to journal 1 which is accomplished by actuating the adjustable supporting means to be described controls the alignment of pipe 7 with the journal 1.

The feed pipe 7, and elbow 11 are guided in their motion of adjustment by means of the key 30 secured to the stationary supporting frame 31 and the keyway 32 formed in or in conjunction with the elbow 11. To move the elbow 11 up and

100

105

110

- down for purposes of adjustment in the preferred form of machine shown, the elbow 11 is connected to a screw 12 in any suitable manner as by means of a pin 13, the screw 12 and elbow 11 being caused to move in an upward or downward direction by an internally threaded sleeve 14 which cooperates with screw 12, the sleeve being rotated on the screw by means of a hand wheel 15 secured to the rotating member 14 by a keyway 10 and key at 17. The threaded sleeve 14 is held against vertical motion by thrust and swivel bearing 16, which provides for rotation of the sleeve about the screw moving the screw 12, elbow 11 and the adjacent end of pipe 7 up and down for purposes of adjustment as aforesaid. To determine with the required degree of accuracy the angle of rotation of member 14, a ratchet wheel 18 is provided which is secured to the wheel 15 and hence to the rotating member 14 by the keyway 20 and key 17. The teeth 18' of this ratchet are equally spaced each space corresponding in the form shown to a suitable and equal arc of rotation of screw 12. Cooperating with the ratchet wheel 18 is a spring detent 9 which engages the teeth on the ratchet wheel in turn, thus having a two-fold purpose, first to enable proper adjustment of the feed pipe and second to prevent the accidental rotation of member 14. The swivel and thrust bearing 16 in which the rotating member 14 is supported and the spring detent 19 are secured to the stationary supporting frame 31 in any suitable manner. The details of this adjustment are capable of considerable variation in design and arrangement.
- 35 The adjusting and leveling device also includes an indicator whereby settlement or depression of the journal 1 is measured or indicated preferably in units corresponding to the adjustment of the feed pipe resulting from turning ratchet 18 one tooth or any integral number of teeth.
- 40 This indicator comprises a feeler shown in the form of a roller 20 arranged to contact the flange 6 on the journal and to swing downwardly therefrom and to be clamped. This roller is mounted 45 upon the arm 29 of bell crank lever 21. The bell crank lever 21 is mounted on a stationary plate 23 to swing about a journal pin 24 which allows the pointer 22 to move along the scale 35 as the roller 20 moves up or down or otherwise toward 50 and from the axis of the cylinder 3. Overlying the depending arm of the bell crank 21 is a strap 40 provided with an arcuate slot 41 and the arm carries a clamping screw 25 operating within the slot to secure the arm in any desired position 55 of adjustment. A spring 26 tends to swing the bell crank lever 21 about the journal pin 24 and to hold roller 20 in contact with flange 6.
- 60 An electric current is supplied to the indicating device by a battery 36 or any other suitable means by way of the leads 26 and 27. The plate 23 being insulated from the cylinder 11 and supported on concrete base 23' is connected to lead 26 and thus included in the circuit. Lead 27 is connected through bell 38 by wire 37 to the bearing 4. When the roller contacts the flange 6, the circuit is closed. This causes the current to flow through the bell 38 producing a warning signal when a predetermined settlement has occurred.
- 70 To maintain the adjustment of the feed pipe which is first located in alignment with the axis of the cylinder and concentric with the hollow trunnion into which it extends, the roller 20 is brought in contact with the flange 6 by moving 75 the pointer 22 along the scale 35. The roller is

then backed away a predetermined distance indicated on the vernier 35. Preferably the scale is calibrated to correspond to the spacing of ratchet teeth 18' and the roller is backed off a distance equal to the distance the elbow 11 may be lowered by the rotation of the ratchet 18 and sleeve 14 through an angle preferably corresponding to the spacing of one tooth 18' from the next or any integral number of teeth and this reading is noted. Ordinarily the spacing of the feeler is uniform for each adjustment.

80 When the bearing 4 wears to a point where the roller 20 comes again in contact with the flange 6, a signal is given by the bell, light or other suitable means actuated by the circuit described or otherwise, or dependence may be placed on an attendant to note the contact. The feed pipe is then adjusted downwardly and leveled by turning ratchet 18 through an angle corresponding to the previously noted reading of the scale 35. 90 With the form of adjustment shown this is done by moving the ratchet wheel in a direction to lower screw 12, bringing the next tooth in contact with detent 19. If the feeler has been moved a distance corresponding to a number of teeth, 100 the sleeve is turned a corresponding number of teeth 18'' as indicated by the scale reading. The feeler 20 is then backed off a predetermined distance preferably a distance corresponding to the previously noted reading of scale 35 and clamped 105 and the operation is repeated.

110 This adjustment may be performed as often as is found necessary or desirable to the operation of the mill, depending largely on the amount of material being treated.

115 Regarding the operation of the feed, it will be understood that as the material accumulates in standpipe 9 the pressure in feed pipe 7 increases. This increases the rate of feed to and through the cylinder making it dependent upon and largely proportionate to the rate at which the material is supplied to standpipe 9. The material, as its treatment is completed, is in the form of machine shown, discharged from the opposite end of the cylinder to that to which it is fed most 120 conveniently by way of hollow trunnion 1' to which it is led through the foraminous end wall 3'', the operation being preferably continuous. The rate of feed may be further controlled relatively to the head by means of ring plate 10' inserted in the union 8' between the adjacent pipe flanges or in any convenient manner. For this purpose these plates are formed in sets having the central opening of different sizes. The rate of feed proportionate to the head is adjusted by inserting the plate 10' having the opening of the proper size.

125 It should be understood that it is not desired to limit the invention to the precise details of the construction disclosed, and that various deviations may be made therefrom without departing from the spirit and scope of the appended claims.

130 What I claim as new and desire to secure by Letters Patent is:

1. The combination with a rotary cylinder having bearings for supporting the cylinder applying the supporting force in a direction transverse to the axis, and an axially placed feed opening, a pipe for delivering material to said feed opening, means for supporting and adjusting the pipe to 140 center it with the opening and align it therewith, means for determining the extent of each adjustment, an indicator for determining the settlement of the cylinder as the bearings wear, facilitating the adjustment of the feed pipe pro- 145 150

portionately to such settlement, said indicator for the cylinder consisting of a pivoted lever having a feeler to engage a concentric portion of the cylinder, the indicator having a pointer moving proportionately to the feeler, a scale cooperating with the pointer and means for holding the feeler in spaced relation to the concentric portion in the direction of settlement.

2. A mill comprising a rotatable drum with its axis at an angle to the vertical, means including a hollow trunnion provided with a packing gland and bearings therefor supporting the drum, a feed pipe delivering material through the gland and into the hollow trunnion, a surface carried by the drum concentric with the axis of said drum, an indicator contacting said surface to indicate

settlement of the drum due to wear of the bearings, a scale in connection with the indicator, and means for supporting for vertical movement and adjusting said feed pipe to correspond to the scale reading.

3. A mill comprising a rotatable drum, means including a hollow trunnion and bearings therefor supporting the drum and provided with a packing gland, a feed pipe delivering material through the gland and into the hollow trunnion, a surface concentric with the axis of said drum and rotating therewith, an indicator contacting said surface to indicate settlement of the drum, and means for supporting and adjusting said feed pipe to the indicated settlement of the drum. 90
